[57] CLAIM

The ornamental design for a game cabinet, as shown and described.

DESCRIPTION

FIG. 1 is a perspective view of a game cabinet embodying my new design.

FIG. 2 is a top plan view of the game cabinet shown in FIG. 1.

FIG. 3 is a front elevational view of the game cabinet shown in FIG. 1.

FIG. 4 is a left side elevational view of the game cabinet shown in FIG. 1.

The back and bottom of the game cabinet are generally planar surfaces, and the right side is a mirror image of the left side.
